UNITED STATES PATENT OFFICE.

HARRY W. BOLENS, OF PORT WASHINGTON, WISCONSIN.

REVOLVING AND SWIVELING CHAIR ADJUSTMENT.

1,245,182.

Specification of Letters Patent. Patented Nov. 6, 1917.

Application filed September 21, 1915. Serial No. 51,783.

To all whom it may concern:

Be it known that I, HARRY W. BOLENS, a citizen of the United States, residing at Port Washington, in the county of Ozaukee 5 and State of Wisconsin, have invented a new and useful Revolving and Swiveling Chair Adjustment, of which the following is a specification.

My invention relates to improvements in 10 adjustments employed in revolving and swiveling chairs, the conventional or usual type of which comprises in its make-up, a metal hub, which may be either cast or struck-up from sheet-steel, and from which 15 radiate the usual legs, the hub and attached legs forming the chair-base. In said conventional or usual type of chair, the hub is bored and receives a post or standard, threaded throughout its length, and having 20 a longitudinal groove extending to its lower end, the groove of the post receiving a spline on what is termed the J-washer. At the upper end of the post is located the stretcher or spider, the connection between the two 25 being permanent and necessarily rigid and secure. The J-washer encircles the post and is mounted on the upper end of the hub, which end may be formed thereat to constitute a bearing or to receive a thrust ball 30 bearing washer, as the case may be. The upper side of the J-washer is usually provided with a plurality of radiating shallow grooves designed to removably engage corresponding ribs formed in the underside of 35 the hub of the hand-wheel, the threads of the latter engaging the threads of the post or standard immediately above the aforesaid J-washer. In this construction, to change heights of the chair-seat, the chair 40 is held by one hand while the hand-wheel is rotated. The J-washer being stationary with the screw, the shallow ribs on the underside of the hub of the hand-wheel glide over the grooves in the upper side of the J-washer, 45 When the chair is occupied the weight of the occupant causes the ribs of the hand-wheel to become locked or engaged with the depressions or grooves of the J-washer and the chair revolves in the bearing on the top 50 of the hub. Thus far I have described one well-known type of chair adjustment, and it is to this particular style of adjustment that my invention is peculiarly applicable and desirable, for the reason that, the base 55 and remainder of the chair being shipped

disconnected and with the J-washer loose on the post, or attached to some part of the chair, the said J-washer is apt to and frequently does drop off and become lost, so that when the chair is put together or assembled it will not work properly by reason of the omission of this important part. 60 Moreover, many times, even when the J-washer is not lost, it is improperly applied. That is to say, it will be inadvertently applied to the post reversely to what it should be, so that its grooves will be on its underside instead of its upperside where they are in position to coact with the corresponding ribs on the underside of the superimposed 65 hand-wheel.

The objects of my invention are to overcome these objections, and the invention consists, first, in preferably threading the post only at that portion thereof which co- 70 operates with the thread of the hand-wheel, that is, above the base, thus leaving a plain cylindrical unthreaded portion of the lower half of the post which uniformly conforms to and fits the hub and which being unthreaded will not unduly wear the same; and, second, in terminating the groove in the post at a point below that occupied by the J-washer and short of the lower end of the post so that the washer and hand-wheel 75 having been positioned properly and relatively on the post and the stretcher permanently secured at the upper end of the post, a separation and consequent loss of these parts is impossible. 80

Referring to the drawing—

Figure 1 is a vertical longitudinal sectional view of a chair-base embodying my improvements; and,

Fig. 2 is a detail view in plan of the J-washer. 95

Fig. 3 is an inverted plan view of the hand-wheel.

Similar numerals of reference indicate similar part in both figures of the drawing. 100

Referring to the drawing in detail, 1 designates the hub, which is bored through out its length as at 2.

Within the hub is located the post or 105 standard 6, and it will be noted that the upper portion thereof, or so much thereof as coacts with the hand-wheel, is threaded, whereas the lower portion is unthreaded and merely plain and cylindrical, as at 7, and neatly fits within the hub. 110

2

Being thus unthreaded, the post will exert a minimum amount of wear upon the interior of the hub contrary to the usual custom of these parts. The post, it will be observed, 5 is provided with a longitudinal groove 8 extending from its upper end and terminates short of the lower end thereof. Immediately above the upper end of the hub and bearing thereon or it may be upon 10 some intermediary anti-friction washer, is the washer 9, usually termed the J-washer, and the same, it will be noted, is provided with a plain bore to receive the post and with an internal spline 10, fitting the groove 15 of the post. Above the J-washer is located the hand-wheel 11, the hub 12, of which is internally threaded to coact with the threads of the post. Upon its underside the hub of the wheel may be provided with shallow radiating ribs 13, and the latter correspond with shallow grooves 14, formed on the upper side of the J-washer, the ribs and grooves coacting in the manner heretofore indicated. Above the hand-wheel may be 20 securely and permanently fastened to the post preferably by heading or upsetting the upper end of the post, at 4, (see dotted lines) any well-known form of spreader.

The result of this arrangement is, that the 25 J-washer as well as the hand-wheel cannot after having been placed upon the post or standard and the stretcher permanently attached, become lost therefrom during shipment, nor can it be improperly positioned 30 thereon, but these parts are always safely confined in proper position with relation to each other so that when the post or standard is mounted in the chair-base these parts are bound to be present and operative.

40 Having thus described my invention, what I claim, is:

1. In a chair-adjustment, the combination

with a bored hub, of a post mounted therein and provided with a groove extending from its upper end and terminating above 45 its lower end, a J-washer encircling the post and having a bearing on the upper end of the hub and provided with an internal spline engaging the groove of the post, a hand-wheel threaded on the post above the J-washer, means between the J-washer and the hub of the hand-wheel whereby the two may be removably engaged, and a stretcher secured at the upper end of the post.

2. In a chair-adjustment, the combination 50 with a bored hub, of a post having its upper portion threaded and its lower portion plain and cylindrical to approximately fit the bore of the hub, said post terminating at its upper end in an enlargement forming a 55 stop and having a longitudinal groove extending from its upper end and terminating short of the lower end thereof, a J-washer fitting the post and having a spline fitting the groove thereof and irremovable from 60 the post, a hand-wheel threaded on the post above the washer, and means between the hub of the hand-wheel and the upper side of the J-washer whereby the two may be 65 removably engaged.

3. In a chair-adjustment, the combination 70 with a hub having a bore, of an adjusting post swiveled therein and having that portion of its length above the hub threaded and below the thread having a plain cylindrical portion bearing in the bore of the hub.

In testimony whereof, I have signed my name to this specification in the presence of two subscribing witnesses.

HARRY W. BOLENS.
